Primary Examiner — Thomas Johannes*Assistant Examiner* — Shawn T Gingrich(74) *Attorney, Agent, or Firm* — Studebaker & Brackett PC(57) **CLAIM**

The ornamental design for an electrical coaxial connector for high-frequency signals, as shown and described.

DESCRIPTION

FIG. 1 is a top view of an electrical coaxial connector for high-frequency signals, which shows my new design;

FIG. 2 is a front view thereof;

FIG. 3 is a bottom plan view thereof;

FIG. 4 is a rear view thereof;

FIG. 5 is a right side view thereof, the left side view is a mirror image thereof;

FIG. 6 is a front, top and left side perspective view thereof;

FIG. 7 is a front, bottom and left side perspective view thereof;

FIG. 8 is a front, top and left side perspective view of the electrical coaxial connector for high-frequency signals put in a condition before use; and,

FIG. 9 is a rear, top and left side perspective view of the electrical coaxial connector for high-frequency signals put in the condition before use.

The broken line portion of the figure drawings is included to show unclaimed subject matter only, and forms no part of the claimed design.
